[57] CLAIM

The ornamental design for a roller cover support for a painting roller, as shown.

DESCRIPTION

FIG. 1 is a perspective view of a roller cover support for a painting roller, showing my new design;
FIG. 2 is a perspective view taken from the opposite end thereof;

FIG. 3 is a cross sectional view taken along line 3—3 of FIG. 1; and

FIG. 4 is a cross sectional view taken along line 4—4 of FIG. 1.
